UNITED STATES PATENT OFFICE.

LOGAN EISELE, OF NASHVILLE, TENNESSEE.

SHIELD FOR GLASS HYPODERMIC SYRINGES.

Application filed May 14, 1921. Serial No. 469,679.

To all whom it may concern:

Be it known that I, LOGAN EISELE, a citizen of the United States, and a resident of Nashville, in the county of Davidson, 5 State of Tennessee, have invented certain new and useful Improvements in Shields for Glass Hypodermic Syringes, of which the following is a specification.

This invention relates to hypodermic syringes having more particular reference to a shield or guard for hypodermic syringes constructed with glass body and glass tips. In syringes of this type, the glass body is commonly constructed with a projecting tip on 10 which the needle holder is mounted, and in the ordinary construction of the syringe and mounting of the needle holder, this projecting tip is extremely liable to fracture, either during use of the syringe, or by accidentally 15 knocking the needle holder against some other object, or when it is attempted to remove the needle holder for cleaning or other purposes.

It is the general object of the present invention to so construct and mount the needle holder as to provide a shield or guard for the projecting tip on the glass body, whereby liability of said tip to breakage will be obviated.

Another object is to provide a construction in which a shield or a guard for all or part of the glass barrel or cylinder proper is provided, as well as a guard for the tip.

Still another object is to construct a shield 35 or guard for the glass cylinder and glass tip in such a manner that the contents of the syringe will come in contact with glass only, thus retaining all of the non-corrodible features of the glass syringes as they are now 40 made, while remedying their disadvantage of fragility.

For further comprehension of the invention and of the objects and advantages thereof, reference will be had to the following 45 description and accompanying drawings in which the various novel features of the invention are more particularly set forth.

Figure (1) of the drawings is a side view of the hypodermic syringe.

Fig. 2 is a view taken at right angles to Fig. 1, partly in section and

Fig. 3 is a bottom plan view.

As shown in the drawings, the reference letter B indicates a metal shield which encases a glass body or cylinder in which the usual piston (not shown) is provided. The

metal shield comprises a rearward cylindrical extension which encases the glass cylinder and a diminished forward extension T' upon which is adapted to be secured the 60 usual hypodermic needle base. The forward extension T' is provided with a tapered boring in which is adapted to be received the forwardly projecting tapered tip T'' of the glass body or cylinder B'. The boring of 65 the metal shield is a trifle larger than the glass tip T' and the glass tip is secured within the metal tip by solder or cement. It will be noted that the glass tip and metal extension are exactly of the same length so that 70 therefore there will be no contact of the contents of the syringe with the metal parts thereof. The use of solder or cement not only prevents any of the contents from passing 75 backwardly between the glass tip and metal extension when the syringe is actuated but also is of importance in the assembling of the parts. I have found that it is very difficult to secure perfect alignment of the tip at the center of the glass body which 80 consequently greatly increases the manufacturing costs, by making the boring of the metal extension a trifle larger than the tip it is therefore not necessary to secure absolute precision in the centering of the glass tip, 85 the solder or cement compensating for any inequalities.

As will be apparent from the above description, a shield or guard for the projecting tip of the glass syringe body is provided whereby danger of breakage of the tip is obviated.

Having thus described my invention, what I claim as new and desire to protect by Letters Patent of the United States is as 95 follows:

A hypodermic syringe comprising a glass body, a metal shield covering said glass body and having a rearward cylindrical extension projecting over the said glass body 100 and a diminished forward extension adapted to support a needle base, said forward extension being provided with a boring, and said glass body having a forwardly projecting tip coextensive with said forward extension, and means between said glass tip and said forward extension for permanently securing said shield to said glass body for preventing the contents of said syringe from being forced backward between said tip and 110 said forward extension.

LOGAN EISELE.
